WEATHER AND LOCK DOOR STRIP

Joseph Sandor, Stamford, Conn.

Application April 6, 1934, Serial No. 719,369

5 Claims. (Cl. 70—74)

The present invention relates to a weather and lock door strip and has for its object to provide a combination structure having both the features of an efficient and effective lock and weather strip.

Another very important object of the invention resides in the provision of a weather and lock door strip of this nature which is simple in its construction, easy to manipulate, strong and durable, comparatively inexpensive to manufacture and install, thoroughly efficient and reliable in use, compact and convenient in its arrangement of parts and otherwise well adapted to the purpose for which it is designed.

With the above and numerous other objects in view as will appear as the description proceeds, the invention consists in certain novel features of construction, and in the combination and arrangement of parts as will hereinafter be more fully described and claimed.

In the drawings:

Figure 1 is an elevation of a door frame with a pair of swinging doors therein showing my improved weather and lock door strip associated therewith.

Figure 2 is an enlarged detail sectional view through the central portion of the mechanism.

Figure 3 is an enlarged detail sectional view taken substantially on the line 3—3 of Figure 1.

Figure 4 is a perspective view of the strips.

Figure 5 is a perspective view of the casing.

Figure 6 is a perspective view of one of the keeper plates.

Figure 7 is a perspective view of the rockable element.

Figure 8 is an enlarged detail sectional view taken substantially on the line 8—8 of Figure 1.

Referring to the drawings in detail it will be seen that the numeral 5 denotes a door frame with a pair of doors 6 and 7 swingably mounted therein on suitable hinges 8 and 9 respectively. This particular door construction has been selected merely for the purposes of exemplification to show the utility of my improved mechanism but it is not my intention to limit my mechanism to this particular use.

The door 6 in its free edge is provided with a slot 10 the central portion 11 of which is deeper than the remaining portions. A casing 12 is mounted in the groove 11 and has an enlarged central portion 14 protruding in the portion 11. Numerals 15 denote combination bolts strips slideable in the casing 12 toward and away from each other and also slideable toward and away from the free edge of the door 7. The inner ends of

the bolts 15 are provided with enlarged heads 16 the opposed faces of which are provided with registering recesses 17 and a spring 18 has ends seated in the recesses 17 and urges the bolt strips away from each other so that the outer beveled ends thereof may engage in keeper plates 19 provided in the frame as indicated in dotted lines in Figure 1. A plurality of bolts 20 are mounted in slots 21 and are threadedly engaged in the bolt strips 15 and springs 22 on these bolts urge these bolt strips into engagement with the free edge of the door 7. Slots 23 in the casing 12 are in registry with the portion 11 at the ends thereof and bolts 24 extend therethrough and are threadedly engaged in the bolt strips 15 and springs 25 are mounted thereon and tensioned to urge the bolt strips toward the free edge of the door 7. Links 26 are engaged with the bolts 24 and are engaged in cranks 27 on a rockable element 28 which has a bolt 29 threaded therein and rockable in an opening 30 in the portions 14 of the casing 12. A lever 31 is keyed on the element 28 and extends through a slot 32 and a registering slot of a plate 33. By swinging the lever 31 it will be readily seen that the strips 15 may be moved toward each other or away from each other.

In the door 7 is a barrel 35 of conventional construction which operates a bolt 36 through a pin and slot connection 36' whereby the bolt 36 may be protruded in locking position as shown in Figure 2 to extend between the inner ends of the bolt strips for holding them in locked position.

It will be noted that the outer edges of the bolt strips are rounded as shown in Figure 8 for engaging with the free edge of the door 7. It will be readily apparent that this mechanism may be used in various other ways from that described. The present embodiment of the invention has been described in considerable detail for the purposes of exemplification since in actual practice it attains the features of advantage enumerated as desirable in the above description.

It will be apparent that changes in the details of construction, and in the combination and arrangement of parts may be resorted to without departing from the spirit or scope of the invention as hereinbefore claimed or sacrificing any of its advantages.

Having thus described my invention, what I claim as new is:

1. A mechanism of the class described comprising a casing open at one side and at the ends

thereof, bolt strips slidably mounted in the casing to move away from each other and toward each other and to move into and out of the casing through the side opening, spring means urging the strips through said side openings, spring means urging the strips away from each other.

2. A mechanism of the class described comprising a casing open at one side and at the ends thereof, bolt strips slidably mounted in the casing to move away from each other and toward each other and to move into and out of the casing through the side opening, spring means urging the strips through said side openings, spring means urging the strips away from each other, means for moving the strips toward and away from each other.

3. A mechanism of the class described comprising a casing open at one side and at the ends thereof, bolt strips slidably mounted in the casing to move away from each other and toward each other and to move into and out of the casing through the side opening, spring means urging the strips through said side openings, spring means urging the strips away from each other, means for moving the strips toward and away from each other, a rotatable element having cranks, links engaged with the cranks, bolts engaged with the strips and extending through slots in the casing, said links being engaged with said bolts, and means for rocking the elements, keeper plates having slots for receiving the outer ends of the strips.

4. A mechanism of the class described comprising a casing open at one side and at the ends thereof, bolt strips slidably mounted in the

casing to move away from each other and toward each other and to move into and out of the casing through the side opening, spring means urging the strips through said side openings, spring means urging the strips away from each other, means for moving the strips toward and away from each other, a rotatable element having cranks, links engaged with the cranks, bolts engaged with the strips and extending through slots in the casing, said links being engaged with said bolts, and means for rocking the elements, keeper plates having slots for receiving the outer ends of the strips.

5. A mechanism of the class described comprising a casing open at one side and at the ends thereof, bolt strips slidably mounted in the casing to move away from each other and toward each other and to move into and out of the casing through the side opening, spring means urging the strips through said side openings, spring means urging the strips away from each other, means for moving the strips toward and away from each other, a rotatable element having cranks, links engaged with the cranks, bolts engaged with the strips and extending through slots in the casing, said links being engaged with said bolts, and means for rocking the elements, keeper plates having slots for receiving the outer ends of the strips, a lock, a bolt operable by said lock and adapted to be projected between the inner ends of the strips to hold them in locked position.

JOSEPH SANDOR.
